United States Patent Office

Des. 187,408
Patented Mar. 8, 1960

187,408

TRAY

Harold W. Hill, Columbus, Ga.

Application October 13, 1958, Serial No. 52,955

Term of patent 14 years

(Cl. D81—17)

The figure is a perspective view of a tray showing my new design.

The side and end not shown are the same as the side and end shown, aside from the electric cord.

I claim:

The ornamental design for a tray, substantially as shown and described.
